BOTTLE ATTACHMENT

Alfred W. Perkins, Newburyport, Mass.

Application November 4, 1933, Serial No. 696,722
Renewed July 16, 1935

1 Claim. (Cl. 65—46)

The invention relates to a bottle attachment and more especially to a bottle-attached cap remover constituting an improvement in the subject matter of Letters Patent #1,916,115, dated

5 June 27, 1933.

The primary object of the invention is the provision of an article of this character, wherein the opening for the reception of a "Crown" cork or cap is so constructed as to provide a centering fulcrum and an extracting lip, whereby on the application of the article the "Crown" cap can be readily and conveniently extracted or removed and the article then may be used as a temporary cap for the bottle so as to maintain the contents 15 thereof fresh for further use.

Another object of the invention is the provision of a cap of this character, wherein in its use as a bottle attachment for a bottle it will snugly embrace the mouth and bottle neck after 20 the original cap of the bottle has been removed in the use of said article as hereinbefore indicated.

A further object of the invention is the provision of an article of this character, wherein the body thereof is expandable to permit the convenient temporary application of the same to the mouth of a bottle and this temporary application will prevent the contents from becoming stale 25 or flat, particularly in the use of the article on a bottle containing ginger ale.

A still further object of the invention is the provision of an article of this character which is unique in its construction, simple in make-up, durable, and inexpensive to manufacture.

35 With these and other objects in view, the invention consists in the features of construction, combination and arrangement of parts as will be hereinafter more fully described in detail, illustrated in the accompanying drawing, which 40 discloses the preferred embodiment of the invention, and pointed out in the claim hereunto appended.

In the accompanying drawing:

45 Figure 1 is a fragmentary elevation of a bottle showing the article constructed in accordance with the invention temporarily applied thereto.

Figure 2 is a vertical sectional view through the article.

50 Figure 3 is a view showing the article applied for the extracting of the "Crown" cap.

Figure 4 is a perspective view of a modified form of the article.

Figure 5 is a sectional view on the line 5—5 of Figure 4.

55 Similar reference characters indicate corre-

sponding parts throughout the several views in the drawing.

Referring to the drawing in detail, A designates a portion of a bottle having the tapered neck which, at the mouth, originally carries the "Crown" cork or cap B of well known construction, the mouth end of the neck of said bottle A being formed with an external bulge 10 and a mouth bead 11, respectively, this being of conventional character.

10 The article or device constituting the present invention, which is an improvement over the subject matter of Letters Patent #1,916,115, dated June 27, 1933, comprises a tubular body 12 having a closed end 13, the body being tapered 15 toward the closed end slightly and having struck therefrom the bulge 14 which is coextensive with the bulge 10 of the neck of the bottle A, so that a bight 15 is present interiorly of this body for snapping engagement of the latter upon the neck 20 of the bottle with the bulge 10 thereof.

15 Interiorly of the body 12, at the closed end 13, is a cork or rubber disk 16 which contacts with the beaded mouth of the neck of the bottle A for the closing thereof and a sealing of the same 25 when the body 12 is snapped onto said neck, as this body telescopes over the same at the mouth end thereof.

20 Formed in the body is the opening 17 having the centering fulcrum portions 18 overhanging an 30 ejecting lip 19, the latter being located at the lowermost point of the opening 17, while the portion 18 is at the uppermost point thereof and these being vertically aligned with each other. The lip 19 has struck therein a strengthening rib 35 20 to increase the extracting strength when the article is used as a cap remover or extractor.

25 In the use of the article the body 12 is brought to a position to have the cap B on the bottle enter marginally the opening 17 and this body 12, when 40 in the position as shown in Figure 3, will permit the extraction or removal of the cap B by pulling upwardly from the lower end of said article, this being clearly apparent from said Figure 3 of the drawing.

30 In Figures 4 and 5 of the drawing there is shown a modified form of article, wherein the body 21 is longitudinally split and the ends at the split are overlapped, the body being preferably made from sheet material having springy quality, while at 50 one end of the body 21 is a channeled annular flange 22 forming a seat for a closure disk or head 23, this being made from metal, and at the inner side thereof is a suitable cork or washer (not shown) which is adapted to seal the open mouth 55

of the bottle. The body 21 is also formed with the bulge 24 which is alike to the bulge 14 in the body 12.

5 The open end of both the bodies 12 and 21 is reinforced by an outwardly struck bead 25.

In the application of the body 21 to the mouth of a bottle it will be apparent that the said body can expand so that the bulge 24 will ride over the bulge 10 in the neck of the bottle A and such

10 body 21 become contracted, thereby firmly embracing the mouth end of the bottle, while the disk or head 23, with its cork or washer, will close the mouth of said bottle neck.

15 It will be understood that in the use of the body 21, the latter is susceptible of embracing the neck of a bottle when wearing the "Crown" cork or cap and, in this instance, the head 23 can be entirely dispensed with so that the body 21, when freed from the bottle neck, can be utilized as a 20 cap remover or extractor and the use of the same can be but a single instance, as such body can be destroyed thereafter. In this mode of use the body 21 is purely and simply a cap extractor or remover.

25 The body 21, at the bulge 24 thereof, at one end of the latter, is slightly outwardly protruded as at

26 and this lies outside of the said body so that the same can be engaged by the finger of the user of the article, so that the body can be pulled upon for the purpose of expanding the said body 21 to enable the free and easy removal of such body from the mouth end of the bottle and this will be clearly obvious from Figures 4 and 5 of the drawing. 5

What is claimed is:

An article of the character described comprising 10 a normally contracted longitudinally split inherently resilient bottle capping body for snugly embracing the neck of a bottle and having the edge portions at the splits considerably overlapping each other, a bulged portion intermediate and 15 circumferentially of the body approximating a bulge in the bottle neck to have portions of said body considerably extended beyond the bulge in the neck to opposite sides thereof, the said body having an opening extended through the bulge at 20 one point thereof, a center fulcrum portion at one edge of said opening, and an ejecting lip at the other edge of said opening opposite the fulcrum and aligned therewith.

ALFRED W. PERKINS.
